(57) **CLAIM**

The ornamental design for a battery charger, as shown and described.

DESCRIPTION

FIG. 1 is a front, right and top perspective view of a battery charger, showing my new design;

FIG. 2 is a rear, left and bottom perspective view thereof;

FIG. 3 is a front perspective view thereof, shown in a used condition;

FIG. 4 is another front perspective view thereof, shown in a battery removed condition;

FIG. 5 is front perspective view thereof, shown in a used condition;

FIG. 6 is a front view thereof;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.

The broken lines on the battery charger depict portions of the battery charger that form no part of the claimed design. The broken lines showing batteries in FIGS. 3, 4, and 5 depict environmental subject matter that form no part of the claimed design.

1 Claim, 11 Drawing Sheets
